BRASSIÈRE

Jack Glick, Bronx, N. Y., assignor to The Gluckin Corporation, New York, N. Y., a corporation of New York

Application May 22, 1946, Serial No. 671,422

7 Claims. (Cl. 2—42)

1

This invention relates to brassières of the type and kind employing a supporting frame for assisting in maintaining the garment upon the body of a wearer, and in proper support of the breasts. More particularly, the invention deals with garments of the type and kind under consideration which are so designed as to produce a low or deep plunge type, that is to say, where the adjacent portions of the breast pockets meet in a double contracted portion or pointed ends disposed preferably below the center parts of the breasts and so as to expose a very deep or low neck portion of the body of the wearer, thus adapting the brassière to outer garments having low necks. Still more particularly, the invention deals with garments of the class described wherein a supporting frame is employed at the lower portions of the pockets, the frame having outwardly diverging loop ends terminating in upper contracted short coupling loop ends disposed at the corner intersections of the breast pockets with a spring loop forming a coupling or bridging member between the side frame parts. The novel features of the invention will be best understood from the following description when taken together with the accompanying drawing in which certain embodiments of the invention are disclosed, and in which the separate parts are designated by suitable reference characters in each of the views, and in which:

Fig. 1 is a front perspective view of a brassière made according to my invention, and omitting complete illustration of the back or body encircling straps as well as the shoulder straps.

Fig. 2 is an inside view of the structure shown in Fig. 1, with parts of the construction broken away; and

Fig. 3 is a plan view of a part of the supporting frame which I employ.

In Fig. 1 of the drawing I have shown one adaptation of my invention in which two substantially similar breast pockets 10—10' are employed, each having a long lower central dart 11—11' and two inner and outer side darts 12—12' and 13—13', extending from the upper and upwardly converging edges 14—14' and 15—15' respectively. These darts give breast shape and contour to the resulting pockets, particularly suitable to the low or deep plunge type of brassière which is shown, that is to say, where

2

the inner sides 14—14' extend to relatively low adjacent inner corners 16—16', which are disposed below the center portions of the pockets, as will most clearly appear from a consideration of Fig. 2 of the drawing. This type of a brassière has the adaptability of exposing at least the upper adjacent side portions of the breasts. Again considering Fig. 2, it will appear that the centers of the breasts when arranged in the pockets 10—10' would be substantially at the positions designated by the reference characters 17—17', thus materially higher than the corners 16—16'.

The lower edge portions 18—18' of the pockets 10—10' are abruptly flared outwardly, in the manner clearly illustrated in Figs. 1 and 2 in extending to the side seams, one of which is shown at 19 in Fig. 1, and the other of which is shown at 19' in Fig. 2. Extending from these side seams, 20 are side and back strap or band portions 20—20' suitably joined and detachably coupled at the back of the wearer in the usual or any desired manner, and as this particular phase of the brassière forms no part of the present invention, no further reference is made thereto.

Attached to the lower edge portions 18—18' of the pockets 10—10', are two channel forming strips, preferably of soft plush-like material 21—21'. These strips extend from the corners 16—16' throughout the major portion of the length of the edges 18—18', but extend upwardly at the sides of the pockets, as seen at 22 in Fig. 1, and 22' in Fig. 2. Within the channels of the strips 21—21' are arranged breast supporting loop portions 23—23' of a supporting frame 24. The loop portions have substantially straight outwardly flared ends 25—25' terminating in in-turned ends 26—26' which are normally positioned at the outer ends of the channels of the strips 21—21'.

Inner end portions of the loops have abruptly converging end portions 27—27' which terminate in inwardly towed or convergently arranged coupling loops 28—28' which fit in the ends of the channels of the strips 21—21' adjacent the corners 16—16', as clearly seen in Fig. 2 of the drawing. These coupling ends are insertable into and removable from the channels of the strips 21—21' through openings 29—29' in providing 50 a detachable mounting of the frame 24 with the

brassière. In some instances, however, the supporting frame or frame members may constitute a permanent part of the breast pockets or the breast covering portions of the garment.

The frame 24 includes a central coupling or bridging member 30 comprising a large spring loop 31 joining the coupling loops 28-28' in shoulder portions 32-32'. On the loop 31 and shoulder portions 32-32' is arranged a tube or sleeve 33 of plastic or other material, preferably of a color in harmony with, or suitably blending with the color of the pockets 10-10' to produce a neat and finished appearance. This covering is also employed to protect the body of the wearer from contact with the frame, particularly when the latter is composed of metal. It will be understood, however, that any type of material can be employed in the frame.

It will be understood that the loop 31 provides a yieldable coupling between the breast pockets 10-10' and by shaping the central portion of the frame in the manner defined, a strong support is provided centrally of the frame in maintaining the corner portion 16-16' of the pockets snugly upon the body of the wearer intermediate the breasts, particularly at the low point in providing what I term the deep plunge brassière construction. This construction of brassière also produces a very desirable support for the breasts in maintaining the same in raised youthful position upon the body of the wearer, and particularly in using shoulder straps 34-34' extending from the upper central portion of each of the pockets.

With my brassière, a firm support of the pockets is provided at the lower intermediate and sides of the brassières, leaving the upper part of the pockets with a flexible non-binding support, and in such manner as to leave part of the breasts exposed at the upper adjacent portion thereof for the purposes hereinbefore stated. In some cases the breasts may be completely covered.

Having fully described my invention, what I claim as new and desire to secure by Letters Patent is:

1. In brassières of the deep plunge type, a pair of pockets, said pockets having curved lower edge portions and upwardly contracted inner and outer side edge portions, the inner edge portions in combination with the lower edge portions contracting in adjacent corners centrally of the garment and at a point below the bust center of said pockets, the lower curved edge portions of said pockets having longitudinal channels, a frame having diverging curved members arranged in said channels, the channels adjacent and in spaced relation to said corners of the pockets having openings facilitating insertion and removal of the curved frame members, and said curved frame members being integrally united in a yieldable bridge portion centrally of the front of the garment.

2. In brassières of the deep plunge type, a pair of pockets, said pockets having curved lower edge portions and upwardly contracted inner and outer side edge portions, the inner edge portions in combination with the lower edge portions contracting in adjacent corners centrally of the garment and at a point below the bust center of said pockets, the lower curved edge portions of said pockets having longitudinal channels, a frame having diverging curved members arranged in said channels, the channels adjacent and in spaced relation to said corners of the pockets

having openings facilitating insertion and removal of the curved frame members, said curved frame members being integrally united in a yieldable bridge portion centrally of the front of the garment, and inner adjacent ends of said curved members being contracted substantially at said corner portions of the pockets.

3. In brassières of the deep plunge type, a pair of pockets, said pockets having curved lower edge portions and upwardly contracted inner and outer side edge portions, the inner edge portions in combination with the lower edge portions contracting in adjacent corners centrally of the garment and at a point below the bust center of said pockets, the lower curved edge portions of said pockets having longitudinal channels, a frame having diverging curved members arranged in said channels, the channels adjacent and in spaced relation to said corners of the pockets having openings facilitating insertion and removal of the curved frame members, said curved frame members being integrally united in a yieldable bridge portion centrally of the front of the garment, inner adjacent ends of said curved members being contracted substantially at said corner portions of the pockets, outer side edges of the pockets joining side and back bands in side seams, and said curved members having straight end portions extending to the seams at a point above lower edge portions of the brassière.

4. A brassière of the character described comprising a pair of pockets, said pockets having contracted front corner portions defined by upper and lower inner edge portions of the pockets, said corner portions being arranged below the bust center of the pockets in providing a deep V-plunge at the upper central portion of the brassière, means for supporting the pockets upon the body of the wearer, said last named means including curved frame members disposed at lower edge portions of said pockets, extending to said corner portions of the pockets, said frame members being detachable with respect to the pockets through openings in lower inner edges of the pockets, and means joining the frame members intermediate and outwardly of the pockets.

5. A brassière of the character described comprising a pair of pockets, said pockets having contracted front corner portions defined by upper and lower inner edge portions of the pockets, said corner portions being arranged below the bust center of the pockets in providing a deep V-plunge at the upper central portion of the brassière, means for supporting the pockets upon the body of the wearer, said last named means including curved frame members disposed at lower edge portions of said pockets, extending to said corner portions of the pockets, said frame members being detachable with respect to the pockets through openings in lower inner edges of the pockets, means joining the frame members intermediate and outwardly of the pockets, and said last named means comprising a downwardly extending curved loop.

6. In brassières of the class described, a supporting frame for supporting peripheral edge portions of the pockets snugly upon the body of the wearer around the breasts, said frame comprising two curved breast encircling members having upwardly contracted inner ends, said contracted ends terminating in short loop members, and a downwardly extending V-shaped spring loop

member integrally joining said short loop members in shoulder portions.

7. In brassières of the class described, a supporting frame for supporting peripheral edge portions of the pockets snugly upon the body of the wearer around the breasts, said frame comprising two curved breast encircling members having upwardly contracted inner ends, said contracted ends terminating in short loop members, a downwardly extending V-shaped spring loop member integrally joining said short loop members in shoulder portions, and the other free and outer ends of said curved members being substantially straight and diverging with respect to the inner ends. 10
